CLAIM

The ornamental design for a gaming machine, as shown and described.

DESCRIPTION

FIG. 1 is a front isometric view of a gaming machine in accordance with the present invention;

FIG. 2 is a front elevation view of the gaming machine illustrated in FIG. 1;

FIG. 3 is a first side view of the gaming machine illustrated in FIG. 1, wherein a second side view of the gaming machine comprises substantially a mirror image of the first side view;

FIG. 4 is a top plan view of the gaming machine illustrated in FIG. 1;

FIG. 5 is a bottom plan view of the gaming machine illustrated in FIG. 1; and,

FIG. 6 is a rear elevation view of the gaming machine illustrated in FIG. 1.

The broken lines in the figures show portions of a button panel and other features of the gaming machine for reference only and form no part of the claimed design.
